(57) **CLAIM**

The ornamental design for a wood splitting wedge, as shown and described.

DESCRIPTION

1. Wood splitting wedge

1.1 : Perspective

1.2 : Bottom

1.3 : Right

1.4 : Left

1.5 : Top

1.6 : Front

The design of a wood splitting tool claimed according to the 6 views is characterized by a handle with a hand guard which does not attach to the wedge at its front or back as usual, but to the side; the rear view of the wood splitting tool is reversed to the front view, but otherwise identical and therefore omitted.
